OIL BURNER

Warren H. De Lancey, Springfield, Mass., assignor to Gilbert & Barker Manufacturing Company, West Springfield, Mass., a corporation of Massachusetts

Application July 23, 1942, Serial No. 452,019

4 Claims. (Cl. 158—28)

This invention relates to improvements in oil burners and, more particularly, to improvements in the ignition means thereof.

The invention has for one object to provide in an oil burner, an ignition supply from a separate generator, such as a magneto, driven from the burner motor and directly supplying the ignition electrodes, as distinguished from a transformer or other means which is electrically connected to the electric service wires supplying other household devices and appliances. The arrangement is characterized in that potential radio interference from the fluttering of the spark is confined to the separate and independent ignition circuit and cannot be fed back into the aforesaid service line.

The invention has for another object the provision in a burner having an ignition magneto, driven from the burner motor, as well as an oil pump also driven from such motor, of means responsive to the speed of the magneto for coupling and uncoupling the pump to the motor whenever the magneto respectively reaches or falls below a predetermined speed.

These objects will best be understood as the detailed description proceeds and they will be pointed out in the appended claims.

The invention will be disclosed with reference to the illustrative embodiment of it in the accompanying drawings, in which:

Fig. 1 is a small-scale side-elevational view of the oil burner;

Fig. 2 is a sectional plan view of the air-supply conduit showing the oil nozzle and ignition electrodes;

Fig. 3 is a sectional elevational view of the motor-driven air-fan, oil-pump and ignition generator;

Fig. 4 is a cross sectional view taken on the line 4—4 of Fig. 3; and

Fig. 5 is a diagram showing the motor circuit in part and the complete ignition circuit.

Referring to these drawings; the burner chosen for illustrative purposes is of the so-called gun type. It includes, as schematically shown in Fig. 1, an electric motor 10 which drives an oil pump 11 and a fan, located within the casing 12. Connected to and projecting from the lower part of the casing 12 is an air-supply conduit 13 having its axis parallel to that of the motor 10. This conduit 13 contains the oil nozzle, ignition electrodes and any other related parts that are necessary or usual in a burner of this kind. Oil is supplied to pump 11 by a conduit 14 and forced by the latter through conduits 15 and 16 to the

nozzle of the burner. Interposed between the conduits 15 and 16 is a pressure-regulating and bypass valve, indicated conventionally at 17. This valve has a by-pass conduit 18 extending back to the suction side of the pump or to the source of oil supply. This valve prevents oil from passing to the nozzle until it has been placed under a predetermined pressure, say for example 125 pounds per square inch. The valve also bypasses some of the pumped oil back to the supply by way of conduit 18, whenever the oil pumped is in excess of the requirement of the burner.

Referring to Fig. 2, the oil nozzle is shown at 19. This nozzle is of the so-called mechanical or pressure-atomizing type. Oil, forced through it under high pressure by pump 11, is emitted in the form of a hollow conical spray and in exceedingly finely divided form like a mist or fog. Air supplied by the fan is forced under relatively low pressure through conduit 13 to mix with the oil spray. The part marked 20 is an air director of any suitable form. Spark electrodes 21 are positioned adjacent the oil spray to ignite the same. Incidentally, these electrodes lie in the path of the air. These electrodes are mounted one in each of two insulators 22 and their outer ends are connected by wires 23 to the source of ignition current. These wires may, as indicated in Fig. 2, pass out of conduit 13 through a removable end closure 24 and into and through a shielding conduit 25 which as indicated in Fig. 1 extends to the casing of motor 10. The nozzle 19 is mounted on a tubular nozzle support 26 to the outer end of which oil feed conduit 16 is connected. The general arrangement and the mounting of the parts in conduit 13 is substantially like that disclosed in the Tapp et al. U. S. Patent No. 2,227,286, dated December 31, 1940, to which reference is made for a more complete disclosure.

The mounting of the fan housing 12 and the connected conduit 13 together with the mounting of the motor 10 is or may be as shown in my U. S. Patent No. 2,262,525, granted Nov. 11, 1941, to which reference is made for a more complete disclosure, if such is necessary or desired.

Referring now to Fig. 3, the motor 10 includes a casing 27 one end of which lies adjacent the fan housing 12 and in line with an opening therein which lies opposite the air inlet 28 of the housing. The stator and rotor are indicated conventionally at 29 and 30, respectively. The rotor shaft is shown at 31 with its inner (left hand) end fixed to the rotor. The fan 32 is fixed to 55 rotor 30, as indicated, and enters the fan hous-

ing through the aforesaid opening. The other end of shaft 31 extends into a compartment 33 formed in the motor casing but partitioned off from the stator and rotor of the motor. In this compartment, the ignition generator is or may be placed. It may be so placed for space-saving reasons. Also, by its location in compartment 33, the metallic walls thereof effectively and completely shield the generator even from the motor itself. The generator, as indicated, is a magneto having a magnetic rotor 34, fixed to shaft 31 and a stator comprising side laminations 35 and a connecting core 36, carrying a coil 37. The magneto may, for example, be constructed as shown in U. S. patent to Harmon et al., No. 2,043,042, dated June 2, 1936, except for the omission of the breaker mechanism and distributor and the use of a single coil in place of the two there shown. The side laminations 35 may be cast into a frame 38 and the latter secured, as indicated, to the motor casing. The ignition wires 23 preferably enter compartment 33 through the shielding conduit 25 for connection to the coil 37. The electrical connections are shown diagrammatically in Fig. 5. The ignition circuit is entirely independent of the circuit in which motor 10 is located, as will be clear from Fig. 5. Also, as will be clear from the preceding description, the ignition circuit is completely shielded from the motor circuit and the motor.

The motor 10 also drives the oil pump 11. This pump may be of any suitable form. As shown, it comprises an internal gear 39 and a spur gear 40 which intermesh and are mounted between a pair of end walls 41 and 42, held apart by a spacer 43. The gear 40 is fixed to a shaft 44 located coaxially of motor shaft 31 and driven therefrom in a special manner as will later appear. The gear 39 is free to rotate within the casing formed by walls 41, 42 and 43. Wall 41 has formed therein inlet and outlet ports 45 and 46, respectively, for the pump, which ports are respectively connected by conduits 47 and 48 to the inlet conduit 14 and outlet conduit 15 above described. This type of pump is more fully disclosed in my U. S. Patent No. 2,230,717, dated Feb. 4, 1941, to which reference is made for a more complete disclosure if such is necessary or desired.

The oil pump is so driven in relation to the magneto that the latter is enabled to be brought up to full speed by the motor 10 before the oil pump is started. This insures that adequate ignition voltage is available to produce ignition sparks between the electrodes before any oil can possibly be emitted from the nozzle 19. This result may be secured by any suitable speed-responsive means which couples the pump shaft 44 to the magneto driving shaft 31 only after the latter has acquired a sufficient predetermined speed. As an example of one means suitable for the purpose there is shown in Figs. 3 and 4, a centrifugal clutch. This clutch has a hollow cylindrical casing 49 fixed to pump shaft 44 and a disk 50 fixed to shaft 31 and located so as to substantially close the open face of the casing 49. The disk 50 carries two weights 51, pivoted one to each of a pair of studs 52 fixed to the disk. Springs 53 tend to draw the weights radially inward and to hold them in their innermost positions shown in Fig. 4. Each weight preferably carries a friction band 54 adapted to engage the inner peripheral wall of casing 49 when the weights 51 are thrown outwardly by sufficient centrifugal force. Thus, these weights, which rotate synchronously with the magneto will, after the latter has acquired the

necessary speed, grip the casing 49 and thereby rotate it and with it the oil pump.

It is to be noted that the fan 28 is also enabled to build up speed before the oil pump is started. 5 This has the important advantages set forth in U. S. patent to Logan No. 1,985,934, dated January 1, 1935. It is desired to retain all these advantages and to secure additional advantages which cannot be secured from the Logan structure and which relates entirely to the ignition system of the burner.

10 The ignition system shown is of the simplest form as will be clear from Fig. 5. It includes simply the magneto generator, the spark electrodes and connecting wires. This system affords so-called continuous ignition—that is, the ignition is operating whenever the burner motor is operating. One trouble that developed in prior burners of this general type was radio interference of a peculiar type. This interference resulted from fluttering of the ignition spark caused by the air current in the path of which the electrodes are located. The fluttering of the spark caused a high frequency disturbance which was fed back into the electric power line because, in 20 accordance with prior practice, the ignition was supplied by a transformer connected to said line. The nearby radio sets connected to the same line suffered from the arrangement. Also, the disturbance was not merely momentary but was prolonged because the ignition remained on as long as the burner was operating. Shielding did not cure this sort of radio interference and it was necessary to use a so-called radio filter for the purpose.

30 With the present system, the radio filter and the ignition transformer are dispensed with and in their place a magneto of simple form is provided. A saving in cost is effected because the magneto is less expensive than the transformer and filter combined. And a saving in space is effected because the magneto can be housed within the motor casing. It is to be noted that this magneto is shielded from the motor and that the 35 wires of the ignition circuit are shielded by conduit 25 and air conduit 13. Consequently, any high frequency disturbance that may be created can be fed back only into the ignition circuit which is entirely separate and independent from the power circuit which supplies the burner motor, radio sets and other electrical devices and appliances. Such disturbances are confined to the ignition circuit and, since the latter is fully shielded, the disturbances cannot be inductively 40 picked up by adjacent wires of the power circuit.

45 The conventional transformer ignition system, commonly used heretofore for burners of the present type, is instantly available to supply ignition sparks whenever the burner is started. That is, the transformer can be brought into full 50 action coincidentally with the burner motor by simply closing a single switch. With the magneto ignition, which is important and desirable as above set forth, there is a slight delay before full ignition voltage is available. Therefore, it becomes necessary to so relate the magneto to the 55 pump as to insure that the magneto will be brought up to speed before oil is emitted from the nozzle.

60 The invention is particularly satisfactory for burners of the so-called pressure-atomizing type but it is not necessarily limited thereto in all its features. The pressure-atomizing nozzle requires the building up of very high oil pressure 65 and this imposes a heavy load on the driving

motor, materially retarding the fan and magneto from building up proper speed. The speed-responsive device enables both fan and magneto to be much more quickly brought to proper speed and the oil pressure is built up afterward and after adequate air and ignition are available for the very first oil emitted from the nozzle. So, too, on stopping of the motor the oil-pump is uncoupled before the magneto and fan stop. As soon as the pump is uncoupled, it stops quickly thereby stopping the flow of oil from the nozzle. But the fan and magneto continue in action for a while due to the momentum of the heavy rotor of the motor and long enough to insure ignition for the last drops of oil which pass the nozzle.

What I claim is:

1. In an oil burner, a nozzle for emitting the oil, means controlling the flow of oil to the nozzle, a conduit for conducting air to the nozzle to mix with the oil, spark electrodes positioned to ignite the oil spray, means for causing a flow of air through said conduit, a magneto, an electrical circuit including the magneto and electrodes, a motor for driving said magneto, and means coordinating the operation of the magneto and oil-flow controlling means to enable flow of oil to said nozzle only when the magneto is moving at sufficient speed to provide ignition sparks at said electrodes.

2. In an oil burner, a pressure-atomizing nozzle, a pump for supplying oil thereto under high pressure, a conduit connecting the pump and nozzle, a pressure-responsive valve interposed in said conduit and opening to allow flow of oil to the nozzle only after the pump has built up the requisite high pressure, spark electrodes positioned to ignite the oil spray from said nozzle, a magneto having its terminals connected to said electrodes, a motor to drive the pump and magneto, means connecting the magneto to the motor to start and stop coincidentally therewith, and means responsive to the speed of the magneto operable to couple the pump to the motor only after the magneto has acquired a predetermined speed which is high enough to generate sufficient voltage and insure a proper ignition spark between said electrodes and operable on deenergiza-

tion of said motor or on a drop in speed thereof below said predetermined speed to uncouple the pump from the motor and stop the flow of oil from said nozzle.

5. 3. In an oil burner, a pressure-atomizing nozzle, a pump for supplying oil thereto under high pressure, a conduit connecting the pump and nozzle, a pressure-responsive valve interposed in said conduit and opening to allow flow of oil to the nozzle only after the pump has built up the requisite high pressure, a conduit for conducting air to the nozzle to mix with the atomized oil, a fan for forcing air at relatively low pressure through said conduit, spark electrodes in the air conduit positioned to ignite the oil spray from said nozzle and positioned also in the path of the air flow, a magneto connected in circuit with said electrodes; an electric motor in a circuit unrelated to the first-named circuit for driving the pump, fan and magneto; means connecting the magneto to the motor to stop and start coincidentally therewith, and means responsive to the speed of the magneto operable to couple the pump to the motor only after the magneto has acquired a predetermined speed which is high enough to generate sufficient voltage to insure a proper ignition spark between said electrodes and operable on deenergization of said motor or a drop in speed thereof below said predetermined speed to uncouple the pump from the motor and stop the flow of oil from said nozzle.

20 4. An electrically-operated fuel-supply and ignition unit for oil burners, comprising, an electric motor having a stationary housing and a revoluble driving shaft, a high tension ignition generator mounted within said housing and directly coupled to said shaft, a fuel pump mounted on said housing and having a driving shaft, and a single means for coupling said shafts operable 25 automatically in response to centrifugal force to couple the shafts and drive the fuel pump when and only when the motor shaft and thus said generator exceeds a predetermined speed to insure an adequate ignition supply before delivery of fuel by the pump.

WARREN H. DE LANCEY.
